UNITED STATES PATENT OFFICE.

AUGUST C. FRANK, OF HAYWARD, CALIFORNIA.

VACUUM-CLEANER NOZZLE.

1,427,200.

Specification of Letters Patent. Patented Aug. 29, 1922.

Application filed September 29, 1920. Serial No. 413,503.

To all whom it may concern:

Be it known that I, AUGUST C. FRANK, a citizen of the United States, residing at Hayward, in the county of Alameda, State 5 of California, have invented a new and useful Vacuum-Cleaner Nozzle, of which the following is a specification in such full and clear terms as will enable those skilled in the art to construct and use the same.

10 This invention relates to a nozzle for vacuum cleaners adapted to the cleaning of the flues of stoves or other places of that character where it is necessary to use a small nozzle to remove the dust or dirt collected therein.

15 A further object of the invention is to provide a nozzle with a scraper which may be used for the purpose of cleaning pipes or other surfaces where accumulations of dust 20 may gather in hard masses.

25 A further object of the invention is to provide the nozzle with a brush which can be easily removed from time to time as the bristles may wear out.

30 Another object of the invention is to provide means whereby the scraper may be detached from the nozzle when it is not to be used.

Other objects of the invention will appear 35 as the description proceeds.

An embodiment of the invention is shown in the accompanying drawings in which the same reference numeral is applied to the same portion throughout, but I am aware 40 that there may be modifications thereof.

Figure 1 is a side elevation of the complete nozzle, a portion being broken away to show a latch.

Fig. 2 is an end view of the complete nozzle looking from the right Fig. 1.

Fig. 3 is a bottom plan view of the nozzle showing the scraper attached.

Fig. 4 is a view of the scraper detached from the nozzle.

Fig. 5 is a side elevation of one of the brush holding clips.

Fig. 6 is a side elevation of one of the brushes.

Fig. 7 is a perspective view of one of the brush holding clips with the spring removed therefrom.

Fig. 8 is a perspective view of the brush holding clip spring by itself.

The numeral 1 indicates a tube which is adapted to be connected to the vacuum 55 cleaner pipe. This tube terminates in a side opening at 2, around which opening are disposed a series of bunches of bristles 3. The bunches of bristles are held in place by means of small channels 4, each of which is secured 60 to the nozzle by means of a rivet 5 and each of which is provided with a lug at 6 to be received in a hole in the nozzle side to prevent the channel from turning.

The channel is also provided with a spring 65 7 which is secured thereto by means of a rivet 8, which spring has teeth at 9 to hold a small bunch of bristles in place.

The bunch of bristles is wound with a wire or thread as indicated at 10. The bunch 70 of bristles thus produced is about the size of the channel 4 and the bunch of bristles is placed in position by means of a sharp instrument engaging the spring 7 and pulling it away from the channel whereupon 75 the old worn out bristles may be removed and the new bunch of bristles inserted in the place of the old ones.

The side of the tube is provided with a pair of guides 11 and 12 upon which slides 80 a shoe 13, this shoe carries a scraper 14 and the scraper has a spring latch 15 riveted thereto for holding the scraper in the position indicated in Figs. 1, 2 and 3.

In use the nozzle is placed on the end of 85 the vacuum cleaner tube and the brush is rubbed around in the place in the stove to be cleaned or any other place to be cleaned and the scraper is made use of to loosen any hard particles of dust or dirt.

What I claim is as follows, but various 90 modifications may be made in the construction shown in the drawings and above particularly described form, within the purview of my invention:

A vacuum cleaner nozzle comprising a tube having an opening on one side, a series of brushes partially around the side opening, a channel member secured to the nozzle for holding each bunch of bristles and a spring 100 for holding the bristles in the channel members.

In testimony whereof I have hereunto set my hand this 18th day of Sept. A. D. 1920.

AUGUST C. FRANK.
